UNITED STATES PATENT OFFICE

ARTHUR JAMES BILLOWS, OF LONDON, ENGLAND; HANNAH ELIZA BILLOWS ADMINISTRATRIX OF SAID ARTHUR JAMES BILLOWS, DECEASED

AERATING AND BOTTLING MACHINE

Application filed April 27, 1928, Serial No. 273,379, and in Great Britain October 27, 1927.

This invention relates to aerating and bottling machines of the kind wherein the bottle is inserted in a bottle-holding device with the neck gripped by a resilient gasket forming part of a filler head, the latter being provided with a snift and liquid supply and means for the crown-cork sealing or closure of the bottle mouth.

The present invention, in its widest aspect, 10 consists in the combination in a machine of the foregoing kind, of an aerating chamber (as is usual in machines heretofore proposed, but without the gasket and crown-sealing devices) and valve mechanism to control the 15 supply of gas to said chamber and aerated liquid therefrom to the filling head, whereby there is provided a single machine which aerates, fills, snifts and crown-seals a bottle.

In the present invention the sealing of the 20 crown cork is effectively performed without the aid of any screw mechanism by means of a simple, easy and quickly hand-actuated cam device which ensures leakless crowning, only one operator being required for working the 25 machine for any carbonated bottled beverage.

For a ready understanding of the invention, reference is to be had to the following description and accompanying sheets of drawings, wherein:—

30 Figure 1 is a front view, partly in section, of a machine constructed in accordance with the invention.

Figure 2 is a right hand side view thereof, the hand wheel and its supporting pedestal 35 being omitted for clearness.

Figure 3 is a left hand side view of the machine, parts of the frame thereof being broken away.

Figure 4 is a top plan view of said machine.

Figure 5 is a view, drawn to an enlarged scale, illustrative of the cam carrier and its cams hereinafter referred to.

Figure 6 is a top plan view thereof.

45 Figure 7 is a central vertical sectional view through the filling head of the machine, showing also cam carrier and snifting valve.

Figure 8 is a vertical sectional view illustrative of the delivery valve of the aerating 50 vessel and valve-actuating means.

Figure 9 is a vertical sectional view illustrative of the gas admission valve and valve-actuating means.

Figure 10 is a fragmentary sectional view, drawn to an enlarged scale, illustrative of the 55 gas admission valve.

Figure 11 is a fragmentary sectional view, drawn to an enlarged scale, illustrative of the snifting valve.

Figure 12 is a vertical sectional view illustrative of the crown gasket and its spring-pressed fingers.

Figure 13 is a vertical sectional view illustrative of the bottle elevating device herein-after referred to.

Figure 14 is a top plan view thereof.

Figure 15 is a top plan view illustrative of the presser plate hereinafter referred to.

Figure 16 is a vertical sectional view taken on line 16—16 of said Figure 15.

Like numerals of reference indicate corresponding parts in the several figures.

In carrying out the invention, and referring first to Figures 1 to 4 of the drawings, the machine consists of a vertically disposed skeleton-like frame 1, 1 on the horizontally disposed top part of which is fixedly secured by its lower flanged cover 2 the mixing or aerating and compressor vessel 3, said cover 2 having formed integral therewith the filling head 4 which depends centrally and vertically therefrom, and on the outside of one of the vertical standards 1, 1 of the frame there is mounted a vertically disposed pump 5, said pump being double-acting and 80 of the tail-rod type.

On a bracket 6 which extends horizontally from the standard 1 aforesaid and above the pump 5 there is mounted a vertically disposed pedestal 7 provided at the top with a bearing 8, in which is rotatably mounted an axle 9, which at its outer end is fitted with a wheel 9 of convenient diameter and width and is provided with an operating handle, whilst the other end of said axle is fitted with a disc crank 10. To the crank pin 11 of said disc-crank 10 there is connected the big end of the connecting rod 12 of the pump 5, from the valve boxes of which two pipes 13, 13, which merge into one, are connected up to the cover 95 100

2 of the aerating vessel 3 aforesaid, so that there obtains an uninterrupted flow of liquid into said vessel when the pump 5 is in action.

To the upper end of the connecting rod 12 there is adjustably affixed, by means of screws 5 14 passed through a slot 15 (see Figs. 5, 6, 7 and 8) in said upper end, a more or less arcuate member or carrier 16 which at each end has adjustably secured thereto, as to rotation, a cam plate, respectively 17 and 18.

10 The cam plate 17 serves to actuate the gas admission valve 19 (see Figures 9 and 10), whilst the cam plate 18 serves to actuate the liquid delivery valve 20 (see Figure 8), the shape and positioning of the cam plate 17 regulating the duration of time said admission valve 19 is open and the cutting out thereof, whilst the shape and positioning of the cam plate 18 regulates the delivery valve 20 as to the amount of aerated liquid to be discharged and the cut out thereof, said cams 17 and 18 actuating said valves 19 and 20 through the movement of the connecting rod 12, that is to say, as the carrier 16 is travelled by the connecting rod in an elliptical path.

25 The gas admission valve 19 (see Figures 9 and 10) is spring-pressed and is slidably mounted in a horizontally disposed chamber 21 formed in the cover 2 of the aerating vessel 3. The tail end of the valve stem 22 is formed with longitudinally disposed slots 23 therein which communicate with the chamber 21, and also with the gas admission pipe 24 which is connected up to a hollow plug 25 which closes the outer end of said chamber 21, and in which plug 25 the slotted tail end of the valve stem 22 is slidably mounted.

30 The valve 19 is provided with longitudinally disposed slots 26 therein, and normally contacts with the valve seat 27 to close the port 28 therein which communicates with the gas passage 29 leading into the aerating vessel 3 aforesaid.

35 With the front face of the valve 19 there contacts the inner end of a horizontally disposed spindle 30 which by its outer end is carried by a sleeve 31 slidably mounted in a chamber 32 in the cover 2 aforesaid, the outer end 33 of said sleeve 32 being conveniently rounded-off and adapted to contact with and travel over the cam plate 17 aforesaid. The inner end of the spindle 30 is slidably mounted in the port 28 and is provided with longitudinally disposed slots 34 which terminate in a circumferential groove 35.

40 The above arrangement is such that when the cam plate 17 engages the end of the sleeve 31, it pushes the same and with it the spindle 30 inwardly, thereby also forcing the valve 19, against the action of its spring, from off the valve seat 27.

45 This allows of the passage of gas from gas admission pipe 24 to aerating chamber 3, by way of the slots 23 in valve stem 22, chamber 21, slots 26 in valve 19, slots 34 and the cir-

50 cumferential groove 35 in the spindle 30, and gas passage 29 to aerating chamber 3 aforesaid, the valve 19 remaining open during such time as the end 33 of the sleeve 31 is in contact with the face of the cam plate 17, but closing directly cam plate 17 slips the end 33 of the sleeve 31.

55 The aerated liquid delivery valve 20 (see Figure 8) is spring-pressed, and is slidably mounted in a horizontally disposed chamber 36 in the cover 2 aforesaid, and with the front face of said valve 20 there engages the inner end of a spindle 37 which is carried by a sleeve 38 slidably in a chamber 39 in said cover 2, said sleeve 38 having a rounded-off end 40 so adapted to contact with the cam plate 18 aforesaid.

60 The chamber 36 communicates by way of a vertically disposed tube 41 with the interior of the aerating vessel 3 aforesaid, and also by way of the passages 42, 43 with the interior (shown in dot-and-dash lines in Figure 8) of the filler head 4 of the machine.

65 The above arrangement is such that when the cam plate 18 engages the end 40 of the sleeve 38, it pushes said sleeve 38 and with it the spindle 37 and valve 20 inwardly, against the action of the spring of said valve 20, thereby uncovering the port 44 which connects together the chamber 36 and the vertically disposed tube 41 aforesaid.

70 This allows of the aerated liquid (provided it be above the level of the top of the tube 41) being forced by the pressure of gas within the vessel 3, out of said vessel 3 by way of tube 41, chamber 36, and passages 42, 43 in the interior of the filling head.

75 The liquid continues to flow so long as the end 40 of the sleeve 38 is on contact with the face of the cam plate 18 aforesaid, the valve 20, directly the end 40 of the sleeve 38 slips the cam plate 18, moving forward under the action of its spring to cover up the port 44, thereby stopping the flow of aerated liquid.

80 The vessel 3 can be drained off, when required, by way of the passage 45 and that part of the chamber 36 behind the valve 20 after removing the plug 46 which closes said chamber.

85 Between the aforesaid valves, and in the filling head 4 and in the left hand side thereof so as to snift away from the operator, there is provided a snifting valve adapted to be actuated by the rounded-off end 47 of the crank pin 11 of the crank disc 10 aforesaid.

90 The snifting valve consists, as shown in Figure 7, in a spindle 48 slidable in a removable plug 49 in a lug 50 depending from the cover 2, and a head 51 slidably in a chamber 52 in the filling head 4 and adapted to close the port 53 therein.

95 The spindle 48 is carried by the rear end of a rectangular frame 54 whose long sides are slidably mounted in grooves 55 (see Figures 3, 8 and 9) in the sides of the filler head

- 4, the front end of said rectangular frame 54 being fitted with a rounded boss 56 adapted to be engaged by the end 47 of the crank pin 11 aforesaid.
- 5 On the crank pin 11 engaging the boss 56, the frame 54, and with it the valve 51, is pushed back against the action of a tension spring 57 interposed between the plug 49 and the rear end of the frame 54 and secured 10 at its ends to said plug and said frame in any suitable manner, thereby uncovering the port 57 and allowing of the snifting to atmosphere by way of port 57.

Further, the aerating vessel 3 aforesaid is 15 at the top thereof (as shown in Figure 1) provided with a safety valve 58 which can be regulated and set to blow off at any required or desired pressure, and to said valve 58 there is connected a vertically depending 20 tube 59 which extends a convenient distance down inside said aerating vessel so that when said safety valve 58 functions, the discharge is of the contained liquid, not of free gas.

Between the vertical standards 1, 1 of 25 the frame of the machine and at the bottom thereof there is provided (as shown in Figures 1 and 3) a hand-operated bottle elevating device.

This device consists (as shown in Figures 30 1 and 3, and also Figures 13 and 14) of a horizontally disposed base plate 60 provided with a vertically disposed upstanding rectangular post 61 of convenient height, and at the lower part of each of two opposite 35 sides of said post 61 there is pivotally mounted the lower end of a gravity cam-shaped plate 62, which plates at a convenient distance back of said post are bolted together by a cross-bar 63, and to said plates 62 and 40 at a convenient distance above the pivots thereof the ends of the arms 64 of a fork-ended handled lever 65 are fixedly connected, said fork-ended handled lever 65 extending upwardly and forwardly a convenient angle 45 and length.

The post 61 aforesaid is at its upper part provided with a central and vertically disposed bore in which is slidably mounted the stem 66 of a block 67 in which is rotatably 50 mounted a horizontally disposed pin 68 whose ends extend beyond the sides of the block 67 and rest on the cam edges 69 of the plates 62 aforesaid, and on the top of said block there is provided a cup-shaped bottle plate 70 55 which is fitted interiorly with a rubber pad 71 on which to stand the bottom of a bottle.

Further, the base plate 60 aforesaid is mounted on a wooden board 72, of a springy nature, which counteracts the shock occasioned at the heaviest point when the crowning of the bottle takes place.

On the inside of each of the oppositely disposed standards 1, 1 and at a convenient height above floor level there is provided an 60 inward and horizontally extending bracket

73 for the removable reception thereon of the bottle elevating device, thus providing for smaller sized bottles being used.

At the top part of the frame of the machine there is pivotally mounted a lever 74 (see Figures 1 and 3) which, by its forked lever end 75, pivotally supports (see Figures 1, 7, 15 and 16) a circular disc or presser plate 76 with an upwardly and inwardly tapered hole 77 therethrough, posited under the filling head 4.

The crowning die (see Figures 7 and 12) consists of a cylindrical member 78 provided externally with vertical grooves in which are fitted spring-pressed fingers 79, each provided at their lower end with an inturned projection 80, said fingers 79, and their springs, being retained in position by a metal sleeve 81 which tightly encases the cylindrical member 78 aforesaid.

The die aforesaid which fits in a circular and centrally disposed recess 82 in the filling head 4 is formed with passages 83 and 84 therethrough, one passage 83 communicating with the liquid delivery passage 42, the other 84 passage 84 communicating with the snifting port 53 aforesaid.

In operation, the pump is connected up with the source of beverage supply. A seal 85 is then inserted through the hole 77 of the presser plate 76 into the crown die (see Figure 8) wherein said seal is held in position by the finger tips 80.

A bottle is then placed on the rubber pad 71 of the bottle elevating device, the neck of the bottle taking in the filling chamber 86 of the filling head 4 and in the hole of the presser plate 76. The handled end of the lever 74, 75 which may be spring-controlled or pedal-actuated, is then depressed to raise 100 the presser plate 76 and compress the rubber die 87 which is carried in and by the filling head 4, tightly on to the neck of the bottle whilst filling under pressure.

The hand wheel 9 is then given a few turns, according to the size of the bottle to be filled, to create a flow of liquid through the pipes 13, and the waterway 89 (see Figure 7) into the aerating, mixing and compressor vessel 3, at the same time the cams 17 and 18 on the carrier 16 function to admit gas to the aerating vessel and then cut off the gas and admit aerated liquid through the tube 31 in the vessel 3 to the bottle and cut off said liquid, whilst the head of the crank pin functions to snift the bottle, thereby rendering bottle breakage impossible, the said cams and head of the crank pin functioning on each revolution of the hand wheel 9 of the pump 5 aforesaid.

When the bottle is filled with aerated liquid, the pump 5 is stopped, and the lever 65 of the bottle elevating device is pressed downwards, with the result that the cam plates 62 swing forward, and by the engage- 130

ment of their cam edges or surfaces 69 with the pin 68 of the slidably mounted block 67, forces said block 67, and with it the bottle, upwards and effect the crown-sealing of said bottle.

5 On release of the lever 65, the cam plates 62 return by gravity to their original position and with them also said crowning lever 65. The lever 74 which effected the compression of the rubber gasket 87 on to the neck of the bottle is released and is returned to its normal position, as does also the rubber-padded cup 70 of the bottle elevating device, whereupon the filled and crown-sealed 10 bottle is removed, facilitated by means of a 15 spring ejector 88 (see Figure 7) located within the cover 2 and extending into the filler head 4 aforesaid.

The hand wheel, when speeding-up of output is required may be driven by any 20 convenient arrangement of power-driven mechanism.

It is to be understood that the crown caps 25 may be fed by hand, or automatically by any convenient arrangement of mechanism.

I claim:—

1. In a bottling machine, in combination, a chamber to contain liquid to be bottled, a pump for delivering liquid to said chamber, 30 a valve controlled gas supply connection to said chamber independent of said pump, a stationary bottle filling head, a valve controlling delivery of liquid from said chamber to said filling head, a pump operating 35 mechanism inclusive of means for actuating said valves, and cap retaining and crimping means within said head.

2. In a bottling machine, in combination, a chamber to contain liquid to be bottled, a 40 pump for delivering liquid to said chamber, a valve controlled gas supply connection to said chamber independent of said pump, a stationary bottle filling head, a valve controlling delivery of liquid from said 45 chamber to said filling head, a pump operating mechanism inclusive of means for actuating said valves, and a snifiting valve connected with said filling head and also under the control of said pump operating mechanism.

3. In a bottle filling machine, a filling head, a chamber to contain liquid for delivery to said filling head, a pair of valves slidably mounted in parallel relation within said 55 filling head respectively controlling delivery of gas to said chamber and liquid from said chamber to said filling head, a pump for supplying liquid to said chamber, pump operating means, and cam means on said pump operating means for actuating said valves.

In testimony whereof I have affixed my signature hereto this 12th day of April, 1928.

ARTHUR JAMES BILLOWS.
